(57) **CLAIM**

I claim the ornamental design for a sole with studs, as shown and described.

DESCRIPTION

FIG. 1 is an enlarged isolated detail perspective view of the 1st stud pattern of my new design for a sole with studs;

FIG. 2 is a FRONT view thereof;

FIG. 3 is a REAR view thereof;

FIG. 4 is a LEFT view thereof;

FIG. 5 is a RIGHT view thereof;

FIG. 6 is a TOP view thereof;

FIG. 7 is a BOTTOM thereof;

FIG. 8 is a PERSPECTIVE LEFT view thereof;

FIG. 9 is an enlarged isolated detail perspective view of the 2nd stud pattern of my new design for a sole with studs;

FIG. 10 is a FRONT view thereof;

FIG. 11 is a REAR view thereof;

FIG. 12 is a LEFT view thereof;

FIG. 13 is a RIGHT view thereof;

FIG. 14 is a TOP view thereof;

FIG. 15 is a BOTTOM thereof;

FIG. 16 is a PERSPECTIVE LEFT view thereof;

FIG. 17 is an enlarged isolated detail perspective view of the 3rd stud pattern of my new design for a sole with studs;

FIG. 18 is a FRONT view thereof;

FIG. 19 is a REAR view thereof;

FIG. 20 is a LEFT view thereof;

FIG. 21 is a RIGHT view thereof;

FIG. 22 is a TOP view thereof;

FIG. 23 is a BOTTOM thereof;

FIG. 24 is a PERSPECTIVE LEFT view thereof;

FIG. 25 is an enlarged isolated detail perspective view of the 4th stud pattern of my new design for a sole with studs;

FIG. 26 is a FRONT view thereof;

FIG. 27 is a REAR view thereof;

FIG. 28 is a LEFT view thereof;

FIG. 29 is a RIGHT view thereof;

FIG. 30 is a TOP view thereof;

FIG. 31 is a BOTTOM thereof;

FIG. 32 is a PERSPECTIVE LEFT view thereof;

FIG. 33 is a PERSPECTIVE RIGHT view of my new design for a sole with studs; and,

(Continued)

FIG. 34 is a BOTTOM VIEW thereof.

The broken lines show portions of the design that form no part of the claim.
